UNITED STATES PATENT OFFICE.

JAMES M. WILLIAMS, OF SANDFORD, FLORIDA.

AUTOMATIC FOLDING CROSSING GATE.

Application filed July 29, 1927 Serial No. 209,323.

This invention relates to a railroad grade crossing and is designed to provide an automatic gate of novel design which will be automatically operable on the approach and withdrawal of a train from the neighborhood of the crossing. The gate itself is made of a soft flexible material guided in tubular guides on a vertical arch spanning the line of vehicular traffic and is suspended from a pulley 5 by a flexible rope or the like secured to a rotary standard fixed at the side of the gate. The standard is connected with a surrounding helical spring, one end of which is secured to a fixed post, the other end being secured to a pulley by which the spring may be put under tension and automatically latched under tension. A determinate distance in front and behind the gate on the track are track instruments controlling the movements 10 of the gate. On approach of a train the forward wheels operate the track instrument, which by a flexible cable rotates the rotatable standard and lowers the gate so as to impede vehicular traffic and simultaneously puts the 15 spring under compression and latches it. On reaching a determinate distance on the other side of the gate the train operates another track instrument connected by flexible means with the latch for the spring and releases its 20 stored power to raise the gate and permit the passage of traffic.

My invention therefore consists of an automatic gate of flexible openwork collapsible material guided vertically in an arch at the 25 crossing by tubular guides and raised and lowered automatically by approaching and withdrawing trains. It consists also of a gate of this general character operated by a rotatable standard at the side of the track, carrying a pulley at the top for raising and lowering the gate and at the bottom a small pulley leading to a track instrument to lower the gate and put tension on the spring and automatically latch the spring under compression so that on transit of the train the 30 stored power of the spring may raise the gate again and permit traffic at the crossing.

It embodies also other more specific features, the novelty of which will be more fully 35 hereinafter described and will be definitely indicated in the appended claims.

In the accompanying drawings illustrating the invention:

Figure 1 is a side elevation of a crossing 40 gate embodying my improvements.

Figure 2 is a top plan view of the same.

Figure 3 is a sectional view on the plane 3-3 of Figure 1.

Figure 4 is a horizontal section on the plane 4-4 of Figure 3.

Figure 5 is a vertical section on the plane 5-5 of Figure 1.

Figure 6 is a vertical section on the plane 6-6 of Figure 1.

Figures 7 and 8 illustrate in elevation and 65 plan, respectively, a modified track instrument.

Referring now in particular to the drawings, 1 represents an arch of tubular iron firmly fixed in cement foundations, or otherwise, in front of a railway at a grade crossing. In sliding relation to the sides of the arch are a plurality of tubular guides 2, 2^a, etc. On the inside of the arch secured in the guides 2 are eyes on which chains 3 may be 70 supported, from the lower side of which chains are dependent flexible open work ropes 4 or the like which form a very light form of gate adapted to reciprocate vertically in the sides of the arch. Supported on the arch 75 centrally is a support for the small pulley 5 to form a guide for a cable 6, the end of which is secured in a grooved pulley 7 of sufficient size to raise the gate by a partial turn of a vertical rotary standard 8 having a thrust 80 bearing in a metallic base 9 steadied by a bracket from a post 10 formed of channel iron 85 bolted in a vertical position on a base at the surface of the ground. The bracket 11 bolted at the top of the channel iron 10 forms a vertical guide for the rotary standard 8, as indicated at 12 in Figure 1. A coil spring 13 of sufficient power to raise the gate incloses the standard 8 and one end of which is secured to a fixed bracket bolted to the standard 10, the 90 other end being fixed to a pulley 14 keyed to the shaft. A flexible cord 15 is firmly secured in the groove of the pulley 14 and is carried thence over a horizontal pulley 16 and passes 95 forward over another small pulley 17 mounted on a cross tie of the rails and thence over a pulley carried by a pivoted lever 18 and secured in an eye at a point beyond the pivotal point. This track instrument carries an arm 19 secured to a cross pin 20 (see Figure 5) 100 supported in brackets beneath the rail base on which is fixed the pivotal arm 18 at the outside of the rail. The arm 19 is at such an angle that it normally lies above the plane 105 of the flange of a wheel so that on the approach of a train the weight of the engine 110 will depress the arm, communicating motion

to the flexible connection, rotating the pulley 14 and connected standard 8, and winding the cord 6 over the pulley 7, thereby straining and latching the spring and lowering the gate. The rotation of the standard 8 tensions the spring and at the close of the movement a collar 21 is rotated until a notch 22 comes into alignment with a dog 23 on a bell crank lever 24 (see Figure 3), to which a small tension spring 25 effects automatic latching relation when the notch comes into alignment by movement of the standard 8 with the notch 23. This effects the locking of the gate in closed position, the tensioning of the spring and latching the same, and when the train reaches the other side of the crossing a determinate distance a cooperating track instrument, such as shown in Figure 6, acts upon the flexible connection 26 (see Figures 1 and 2), withdrawing the latch end of the bell crank lever 24 by raising the dog 23, thereby releasing the stored energy of the spring 13 and raising the gate. The track instrument last mentioned is somewhat similar in construction to the one already described, being similarly mounted on the underside of the rail with a fixed arm 27 raised to a vertical position when the gate is closed by approach of a train and which, after a determinate distance of the train from the crossing, is automatically depressed by the flange of a wheel and communicates its motion to release the spring and raise the gate.

A modified form of track instrument is illustrated in Figures 7 and 8 in which is shown a slotted bell crank lever 28 which is pivoted on a post riveted under the head of the rail, and a cooperating pivoted member 29 carries a pin 30 guided in a slot in one of the bell crank arms. Spiral springs 30, 30^a cooperate on the bell crank and the arm 29 to afford a strong mounting for the parts of the track instrument. The passage of a wheel causes a flange to engage the flaring front end 31 of the member 29, causing it to trip the spring.

It will thus be seen that I have provided

an automatic grade crossing gate of light weight and capable of being raised and lowered so as to be flexible and not liable to injure any person or vehicle in its descent, and capable of being automatically raised and lowered by the passage of trains to protect the crossing.

Having thus described my invention, what I claim as new and desire to secure by Letters Patent is:

1. An automatic crossing gate flexibly supported centrally of an arch before the crossing, comprising a foldable openwork fabric guided on sleeves slideable on the arch, automatic track instruments a determinate distance at the sides of the crossing, flexible means for operating the gate, a lever on the track instrument operated by a passing train and connected with said flexible means, a rotatable spring pressed standard at the side of the arch to lower the gate on approach of a train and raise the same when it passes.

2. An automatic gate for a railway grade crossing, comprising a light-weight gate movable in sleeves on the sides of an arch at the crossing, a vertical rotatable standard at the side of the arch, a track instrument a determinate distance in advance of the crossing to rotate the standard and lower the gate, means for simultaneously latching a spring to store power to raise the gate, and a track instrument a determinate distance beyond the crossing to release the stored energy in the spring and automatically raise the gate.

3. An automatic gate for a grade crossing, comprising an arch in front of the crossing, sleeves slideable in its sides, a rotatable standard at the side, a spring adapted to raise the gate, a track instrument operated by an approaching train to lower the gate and simultaneously wind the spring, a latch to hold it wound, and a second track instrument beyond the crossing to release the latch, whereby the stored energy of the spring acts to raise the gate and permit transit of traffic.

In testimony whereof I affix my signature.

JAMES M. WILLIAMS.
